(57) **CLAIM**

The ornamental design for a battery pack connector, as shown and described.

DESCRIPTION

FIG. 1 is a first perspective view of a battery pack charging receptacle according to a first embodiment.

FIG. 2 is a front side view of the battery pack charging receptacle of FIG. 1.

FIG. 3 is a first perspective view of a battery pack charging receptacle according to a second embodiment.

FIG. 4 is a front side view of the battery pack charging receptacle of FIG. 3.

FIG. 5 is a first perspective view of a battery pack connector according to a third embodiment.

FIG. 6 is a front side view of the battery pack connector of FIG. 5.

FIG. 7 is a first perspective view of a battery pack connector according to a fourth embodiment; and,

FIG. 8 is a front side view of the battery pack connector of FIG. 7.

The broken lines in the drawings depict portions of the battery pack connector that form no part of the claimed design.
